(74) Attorney, Agent, or Firm — Lerner David LLP

(57) **CLAIM**

The ornamental design for a litter tray, as shown and described.

DESCRIPTION

FIG. 1 is a perspective view of a litter tray showing my design.

FIG. 2 is a left side view of the litter tray.

FIG. 3 is a right side view of the litter tray.

FIG. 4 is a front elevation view of the litter tray.

FIG. 5 is a rear elevation view of the litter tray.

FIG. 6 is a top view of the litter tray; and,

FIG. 7 is a bottom view of the litter tray.

The dashed broken lines depict portions of the litter tray that form no part of the claimed design. The dot-dash broken lines represent the boundary of the claimed design and form no part thereof.

1 Claim, 5 Drawing Sheets
